UNITED STATES PATENT OFFICE.

CHRISTIAN AALBORG, OF WILKINSBURG, PENNSYLVANIA, ASSIGNOR TO WESTINGHOUSE ELECTRIC AND MANUFACTURING COMPANY, A CORPORATION OF PENNSYLVANIA.

IGNITION MECHANISM.

1,277,348.

Specification of Letters Patent.

Patented Sept. 3, 1918.

Application filed August 28, 1915. Serial No. 47,885.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Ignition Mechanisms, of which the following is a specification.

My invention relates to ignition mechanisms and particularly to unitary structures in which are assembled the several ignition devices that are embodied in the ignition systems of internal combustion engines.

My invention has for its object to provide a mechanism of the above indicated character in which the usual separate devices of an ignition system are combined in a simple manner to form a compact unitary mechanism.

When the several functions of an ignition system are performed by separate devices, it is necessary to employ a large number of conductors to interconnect their respective terminals. Since the electrical connections employed in the electrical systems of internal combustion engines, or of motor vehicles, are subjected to severe vibration, it is highly desirable that the number of conductors and external connections should be reduced to a minimum.

In the present arrangement, I combine the usual induction coil, condenser, interrupter and distributor, in a unitary mechanism. The movable members of the interrupter and distributor are operatively connected to a single rotating member. The electrical connections between the several devices, which are completed at the place of manufacture, are all within a protecting casing. The connections may be more permanent and substantial than is possible in ignition systems as usually constructed. Derangement of the system because of grounded conductors, loose connections and similar causes is thereby avoided. A mechanism constructed as above described may be easily and quickly installed, thereby effecting a considerable saving in time and labor.

In the accompanying drawings, Figure 1 is a view in transverse section, of a portion of a dynamo-electric machine with an ignition mechanism constructed in accord-

ance with my invention, applied thereto. Fig. 2 is a view, in longitudinal section, of the ignition mechanism of Fig. 1, the dynamo-electric machine being shown in end elevation. Fig. 3 is a view, in longitudinal section, taken on line III—III of Fig. 1. Fig. 4 is a view, in transverse section, illustrating the position of the condenser and its terminal connections. Fig. 5 is a plan view of the interrupter mechanism. Fig. 6 is a diagrammatic view of circuits and apparatus employed in connection with my invention.

Referring particularly to Figs. 1 and 2, an ignition mechanism 1 comprises a casing 2 which is constructed in three detachably connected parts that are mounted in axial alinement. An intermediate part 3, which may be of cast iron or other suitable material, is provided with a laterally projecting portion 4 that is adapted to be connected to the frame of a dynamo-electric machine 5 or other suitable stationary support.

A rotatable shaft 6, which extends longitudinally within the casing part 3, is connected, by means of a worm-gear mechanism 7, to a shaft 8 which extends transversely into the casing and may be operatively connected to the shaft of the dynamo-electric machine 5 or to any rotating member of the internal combustion engine. A condenser 8^a is located within a chamber which is adjacent to and partly surrounds the shaft 6.

The lower portion of the casing comprises a member 9 of insulating material which is detachably connected to the intermediate member 3 by suitable screws or bolts 10. An induction coil 11, which is mounted in the lower portion of the casing, comprises a primary winding 12, a secondary winding 13, and a core member which is composed of laminations 14 of substantially T-shape. The horizontally-extending portions of the laminations 14 may be so bent relatively to the vertically extending portions that they project radially outward in various directions from the central portion of the core member. The laminations constitute a considerable portion of the magnetic circuit of the coil. Their arrangement insures, however, that the magnetic circuit does not include any closed ring of conduct-

ing material in which eddy currents may be produced. The induction coil is retained in position by cement or other suitable insulating material.

5 The upper portion of the casing 2 consists of a member 15 of insulating material that is detachably connected, by means of spring clips 16, to a disk 17. The latter is provided with a sleeve portion 18 rotatably mounted on the shaft 6 and extending into the intermediate casing member 3. An interrupter 19 and a distributer 20 are inclosed within the member 15, the rotatable members of these circuit-controlling mechanisms being secured to the shaft 6 for rotation therewith.

10 The details of the interrupter mechanism 19 are illustrated in Fig. 5. A cam disk 21, which is provided with projections 21^a, corresponding in number to the cylinders of the engine with which it is associated, is rigidly secured to the shaft 6. A pivotally mounted lever 22 is provided, at an intermediate portion, with a projecting portion 23 to be engaged by the projections 21^a when the shaft 6 rotates. The lever 22 carries, at its outer end, a contact member 24, which coacts with a stationary contact member 25 to control the primary circuit of the induction coil. A spring 26 normally maintains the lever 22 in its illustrated position with the contact members 24 and 25 in engagement. The stationary portion of the interrupter is mounted on the disk 17. The latter is provided with slots 27 which coact with screws 28 to limit movements of the disk relatively to the casing member 3.

15 The distributer mechanism 20 comprises a rotatable member 29, which carries a spring-pressed brush 30 that is electrically connected to a contact ring 31. The member 15 is provided with contact pieces 32 embedded therein which coact with the brush 30 and which correspond in number to the cylinders of the internal combustion engine. The member 15 thus constitutes the stationary portion of the distributer and a removable cover member for inclosing the circuit-controlling mechanism. A safety 20 spark gap is provided by a member 33, which is electrically connected to the brush 30, and the shaft 6, which is grounded. Any damage that might be caused by excessive voltages or loose connections is thereby effectively prevented.

25 The electrical connections between the secondary winding 13 of the induction coil 10 and the distributer 20 are shown in Fig. 8. An electrical conductor 34, which is embedded in the insulating material surrounding the induction coil, is soldered or otherwise suitably connected to a terminal member 35. A spring-pressed brush 36, which is slidably mounted in a member 37 of conducting material, engages the termi-

nal 35. A spring-pressed brush 38, which is mounted in the upper portion of the member 37, engages the contact ring 31 that is mounted on the lower surface of the distributer arm 29.

30 Reference may now be had to Fig. 6, in which the electrical connections of the several ignition devices are diagrammatically illustrated. The interrupter cam 21 and the distributer arm 29 are represented as being operatively connected to the armature shaft of the dynamo-electric machine 5. The dynamo-electric machine, which may furnish current for lighting and ignition purposes, or for charging a storage battery, is provided with a series field winding 40 and a shunt field winding 41. The primary coil 12 is connected in circuit with the armature of the dynamo-electric machine, the secondary coil 13 being connected to the distributer brush 29. The several contact pieces 32 are connected to corresponding spark plugs 42 of the internal combustion engine. The terminals of the condenser 8 are respectively connected to the contact members 24 and 25 of the interrupter.

35 The charging circuit of the dynamo-electric machine is controlled by a cutout 43 which prevents the battery from discharging through the generator. The cutout 43 comprises a stationary magnetizable member 44, a coil 45 that is in series with the series field winding 40 and a coil 46 that is in series with the shunt field winding 41. One terminal of each of the coils 45 and 46 is connected to a stationary contact member 47. An armature 48, which is pivotally mounted, carries a contact member 49 which coacts with the contact member 47. A spring 50 tends to maintain the armature 48 in its uppermost position to disengage the contact members.

40 The operation of the ignition mechanism corresponds to that of systems embodying separate devices. When the armature shaft 110 is rotated by the internal combustion engine, the interrupter cam 21 actuates the lever 22 to separate the contact members 24 and 25 and thereby open a circuit comprising a storage battery, the contact members 24 and 25 and the primary winding 12 of the induction coil. A high electromotive force is generated in the secondary circuit which comprises the secondary winding 13, the distributer brush 30, contact piece 32 and the spark plug 42 with which the distributer is connected at that instant, and a spark is caused in the corresponding engine cylinder. This operation is repeated at each succeeding engagement of a projection on the interrupter cam 21 and the coacting projection on the interrupter lever 22.

45 The timing of the ignition spark is controlled by an arm 52 which is connected to the rotatable disk 17 upon which the sta-

tionary portions of the interrupter and the distributor are mounted. The actuation of the arm 52 varies the angular relation of the stationary portion of the interrupter mechanism and the casing member 15 relatively to the shaft 6. The adjustment of the arm 52 causes the operation of the interrupter mechanism to occur at an earlier or later point in the stroke of the engine 10 piston according to the direction in which it is adjusted.

When the generator is operated at an increasing speed, current traverses a circuit comprising the series field winding 40, series 15 coil 45, shunt coil 46 and shunt field winding 41. When the speed reaches the predetermined rate at which the coils 45 and 46 are sufficiently energized, the armature member 48 is drawn downwardly against 20 the force of the spring 50 to effect the engagement of contact members 47 and 49. The charging circuit of the generator, which is thereby completed, extends from one terminal of the generator through series field 25 winding 40, series coil 45, contact members 47 and 49, and armature member 48 to ground and thence to the grounded side of a storage battery which is connected to the other terminal of the generator. This circuit is maintained as long as the voltage of 30 the generator exceeds that of the battery.

If, for any reason, such as, for example, a decrease in speed, the voltage of the battery exceeds that of the generator, current tends 35 to flow in the reverse direction through the charging circuit, and the series coil 45, which normally assists the shunt coil 46, now opposes the latter, and the spring 50 draws the armature member 48 upwardly to separate 40 the contact members 47 and 49 and thereby open the charging circuit.

In addition to the advantages above set forth, an ignition mechanism constructed in accordance with my invention may be 45 easily and readily secured to any mechanism in connection with which it is to be operated. Since substantially all of the rotating parts of an engine extend horizontally, the device may be mounted in a vertical 50 position and its operative connection to a horizontal shaft readily effected. By arranging the intermediate portion of the casing to be secured to a suitable support, the upper and lower portions of the casing may 55 be easily and readily removed for inspection or repair of the parts inclosed therein.

I claim as my invention:

1. In an ignition mechanism, the combination with a substantially cylindrical casing having a plurality of parts comprising 60 an intermediate part and other parts detachably connected thereto, and a circuit-controlling mechanism within said casing, of a driving shaft extending into the side of 65 said intermediate part at right angles to

the axis of the casing and operatively connected to said mechanism.

2. In an ignition mechanism, the combination with a casing comprising a plurality of detachably connected parts in axial alignment, of a rotatable shaft and a condenser in one of said parts, a circuit controlling mechanism in a second of said parts operatively connected to said shaft, and an induction coil in a third of said parts electrically 70 connected to said circuit controlling mechanism. 75

3. In an ignition mechanism, the combination with a casing comprising a plurality of detachably connected parts, of a rotatable 80 shaft in one of said parts, a circuit-controlling mechanism in a second of said parts operatively connected to said shaft, an induction coil in a third part of said casing 85 electrically connected to said circuit controlling mechanism, and means for driving said shaft.

4. In an ignition mechanism, the combination with a casing having a plurality of parts comprising an intermediate part and a 90 plurality of parts detachably connected thereto, of a rotatable shaft in said intermediate part, an interrupter and a distributor in one of said detachable parts and operatively connected to said shaft, and an 95 induction coil in a second of said detachable parts.

5. In an ignition mechanism, the combination with a casing member having means for securing to a suitable support, and a rotatable shaft within said casing member, of a member rotatable relatively to said casing member, a circuit-controlling mechanism connected to said rotatable member and operatively connected to said shaft, and a removable cover member for inclosing said 100 mechanism. 105

6. In an ignition mechanism, the combination with a casing member having means for securing to a suitable support, and a rotatable shaft within said casing member, of a member rotatable relatively to said casing member, a circuit-controlling mechanism connected to said casing member and operatively connected to said shaft, said mechanism comprising a distributor brush and a removable cover member of insulating material having a plurality of spaced contact members for coacting with said brush. 110 115

7. In an ignition mechanism, the combination with a casing member having means for securing to a suitable support, and a rotatable shaft within said casing member, of a member rotatable relatively to said casing member, a circuit-controlling mechanism 120 connected to said rotatable member and operatively connected to said shaft, said mechanism comprising a distributor brush and a removable cover member of insulating material connected to said rotatable member 125 130

and having a plurality of spaced contact members for coacting with said brush.

8. In an ignition mechanism, the combination with a casing member having means for securing to a suitable support, and a rotatable shaft within said casing member, of a condenser adjacent said shaft, a circuit-controlling mechanism operatively connected to said shaft, and a driving shaft extending into said casing member transversely to said shaft and operatively connected thereto.

9. In an ignition mechanism, the combination with a casing member, a rotatable member therein, and a shaft extending into said casing member and operatively con-

nected to said rotatable member, of an interrupter and a distributor operatively connected to said rotatable member, means for varying the angular relation of said interrupter and distributor relatively to said shaft, a second casing member of insulating material connected to the other casing member and in axial alinement therewith, and an induction coil in the second casing member electrically connected to said distributor.

In testimony whereof I have hereunto subscribed my name this 20th day of Aug. 1915.

CHRISTIAN AALBORG.
